UNITED STATES PATENT OFFICE.

ALFRED J. FRUEH, OF NEW YORK, N. Y.

TOY ANIMAL.

1,227,129.

Specification of Letters Patent. Patented May 22, 1917.

Application filed July 18, 1916. Serial No. 109,880.

To all whom it may concern:

Be it known that I, ALFRED J. FRUEH, a citizen of the United States, residing at the city of New York, borough of Manhattan, 5 in the county and State of New York, have invented certain new and useful Improvements in Toy Animals, of which the following is a full, clear, and exact specification.

This invention relates to an improvement 10 in toy animals, and has for one of its objects to provide a toy animal consisting of a plurality of separable parts or sections whereby it may be taken apart and put together.

Other objects will in part be obvious and 15 in part be pointed out hereinafter.

To the attainment of the aforesaid objects and ends my invention consists in the novel 20 details of construction, and in the combination, connection and arrangement of parts hereinafter more fully described and then pointed out in the claims.

In the accompanying drawings showing two illustrative embodiments of the invention—

25 Figure 1 is a perspective view of a toy animal constructed in accordance with the invention;

Fig. 2 is a top view thereof;

Fig. 3 is a perspective view showing the 30 parts of the toy animal separated;

Fig. 4 is a perspective view of a modified construction of the toy animal;

Fig. 5 is an end view thereof,

Fig. 6 is a view similar to Fig. 3 showing 35 the parts separated;

Fig. 7 is a detail view of the foot structure shown in Fig. 4; and

Fig. 8 is a detail view of the head structure shown in Fig. 4.

40 Referring to Figs 1, 2 and 3 of the drawings, the toy animal, which for purposes of illustration is shown in the form of a bear, has a body comprising a plurality of flat, longitudinal body sections 10, 11, 12, 13 and 14, having their side surfaces parallel 45 with one another. The several body sections may be of the same thickness, or certain of them may be thicker than the others, and, of course, the number of the body sections employed may be varied as desired.

The several body sections are provided with transversely extending perforations 15 registering with one another when the sections are properly assembled, and they are 50 held in their assembled positions by means

of pins 16 which extend through the registering perforations 15 and frictionally engage the walls thereof. The length of each of the pins 16 is equal to the combined thickness of the several body sections so that the 60 ends of the pins will be flush with the outer side surfaces of the outer body sections.

As shown in Figs. 1, 2 and 3 the several legs and feet 17 of the toy animal are formed integral with one another and with certain 65 of the body sections 10 and 14 so that their positions relatively to the body of the animal cannot be varied.

The head section 18 of the animal is preferably formed of a plurality of flat, longitudinal members, as shown in Figs. 1, 2 and 3, secured to one another by a pin 18', but it will, of course, be understood that the section 18 may be formed in one piece if desired without departing from the spirit of 75 the invention. The head section is provided with a centrally positioned, rearwardly extending portion 19 having a rounded rear wall 20 shaped as an arc of a circle and adapted to form a rotatable joint with a 80 correspondingly curved recess 21 formed in the central body section 12. The intermediate body sections 11 and 13 are provided with forwardly extending portions 22 having rounded front walls 23 shaped as arcs 85 of a circle and adapted to form rotatable joints with correspondingly curved recesses 24 formed in the head section 18. The head section 18 is held in position upon the body by means of a pin 25 frictionally engaging 90 the perforations 26 formed in the projecting portions 22 of body sections 11 and 13, and the perforation 27, formed in the projecting portion 19 of the head section 18, it being understood that the perforations 26 95 and 27 will register with one another when the head section 18 is properly positioned with respect to the body formed by the assembled body sections 10, 11, 12, 13 and 14.

The rounded rear wall 20 of the projecting portion 19 and the rounded front walls 23 of the projecting portions 22 are shaped as arcs of circles of the same size, and the perforations 26 and 27 are so arranged that the pin 25 will be at the centers of the circles of which the arcs are a part so that the head section 18 may be rotated about the pin 25 to assume different positions relative to the body of the animal.

Referring now to the modification of the 110

invention as shown in Figs. 4, 5 and 6, in which figures the toy animal is shown as representing a bear of a different type than that shown in Figs. 1, 2 and 3, the body of 5 the animal comprises a plurality of flat, longitudinal body sections 28, 29, 30, 31, 32, 33 and 34 having registering perforations 35 to frictionally receive pins 36 by means of which the body sections are held together 10 as above described with respect to Figs. 1, 2 and 3. The head section 37 is rotatably mounted upon a pin 38 and is provided with curved surfaces co-acting with correspondingly curved surfaces formed on certain of 15 the body sections in the manner above described with respect to Figs. 1, 2 and 3.

In the modification of the invention shown in Figs. 4, 5 and 6, the legs of the animal are movable with respect to one another and 20 with respect to the body, and the feet are movable with respect to the legs. As shown the legs are formed of pairs of spaced leg sections 39 having their upper ends 40 rounded to form rotatable joints with correspondingly shaped recesses 41 formed in 25 the body sections 28, 30, 32 and 34, the leg members being pivotally mounted upon pins 42 frictionally engaging registering perforations 43 formed in the leg members 39 and 30 in the body sections 29, 31 and 33 respectively.

The lower ends 45 of the leg sections 39 are also rounded and form rotatable joints with correspondingly shaped recesses 46 35 formed in the foot sections 47. Each of the foot sections 47, which is provided with an upwardly extending portion 48 positioned between the spaced leg sections 39 of its co-acting leg, is rotatably mounted upon a pin 49 extending through registering perforations 50 and 51 formed in the leg sections 39 and in the portion 48 of the foot section 47 respectively.

If desired the various sections of which 45 the toy animals are composed may be lettered or numbered to indicate the order in which they are to be assembled in order to assist in the building up of the completed animal.

50 Having thus described my said invention what I claim and desire to secure by Letters Patent is:—

1. A toy having the form of an animal comprising a plurality of body sections assembled to form the body of the animal, said body sections having perforations formed therein adapted to register with one another when said body sections are assembled, and means extending through said registering perforations and frictionally engaging the walls thereof to hold said body sections assembled, substantially as specified.

2. A toy having the form of an animal comprising a plurality of body sections assembled to form the body of the animal,

said body sections having perforations formed therein adapted to register with one another when said body sections are assembled, and removable means extending through said registering perforations and frictionally engaging the walls thereof to hold said body sections assembled, substantially as specified.

3. A toy having the form of an animal comprising a plurality of body sections assembled to form the body of the animal, said body sections having perforations formed therein adapted to register with one another when said body sections are assembled, and pins extending through said registering perforations frictionally engaging the walls thereof to hold said body sections assembled, the length of said pins being equal to the combined thickness of said plurality of body sections, whereby the ends of said pins will be flush with the outer side surfaces of the outer body sections, substantially as specified.

4. A toy having the form of an animal comprising a body provided with a recess having a rounded inner end, a head section provided with a projection extending within said recess, said projection having a rounded end co-acting with the rounded inner end of said recess to form a rotatable joint, and means rotatably supporting said head section upon said body, substantially as described.

5. A toy having the form of an animal comprising a plurality of longitudinal body sections assembled to form the body of the animal, means to hold said body sections assembled, one of said body sections being provided with a rounded recess, others of said body sections being provided with projections extending beyond said recess, a head section having a rounded projection co-acting with said recess to form a rotatable joint, and means extending through the projections of said head section and said body sections for rotatably supporting said head section upon said body, substantially as specified.

6. A toy having the form of an animal comprising a plurality of longitudinal body sections assembled to form the body of the animal, means to hold said body sections assembled, one of said body sections being provided with a rounded recess and certain others of said body sections being provided with rounded projections, a head section having a rounded projection co-acting with said recess and rounded recesses co-acting with said first-named projections to form a rotatable joint between said head section and said body sections, and removable means rotatably supporting said head section upon said body, substantially as specified.

7. A toy having the form of an animal comprising a plurality of longitudinal body

sections assembled to form the body of the animal, means to hold said body sections assembled, certain of said body sections being provided with rounded recesses, leg sections 5 having rounded upper ends co-acting with said recesses to form rotatable joints, said leg sections having rounded lower ends, and detachable foot sections pivotally secured to said leg sections and having rounded 10 recesses co-acting with the rounded lower ends thereof to form rotatable joints, substantially as specified.

Signed at the city of New York, in the county and State of New York, this 22d day of May, one thousand nine hundred and sixteen.

ALFRED J. FRUEH.
